(57) **CLAIM**

The ornamental design for a article restraint for use in a vehicle, as shown and described.

DESCRIPTION

FIG. 1 is a top perspective view of an article restraint for use in a vehicle, showing my new design;

FIG. 2 is a bottom perspective view thereof;

FIG. 3 is a top perspective view of a second embodiment of an article restraint for use in a vehicle showing my new design; and,

FIG. 4 is a bottom perspective view of FIG. 3.

The broken lines shown in all of the figures are for illustrative purposes only and form no part of the claimed design. The strap portion of the article restraint for use in a vehicle is shown broken away to indicate indeterminate length.
